(57) **CLAIM**

The ornamental design for a ceiling fan motor housing, as shown and described.

DESCRIPTION

FIG. 1 is a top perspective view of a ceiling fan motor housing showing my new design, shown in the environment of a ceiling fan;

FIG. 2 is a bottom perspective view of the ceiling fan motor housing of FIG. 1, but shown without the ceiling fan environment;

FIG. 3 is a top view thereof;

FIG. 4 is a bottom view thereof; and,

FIG. 5 is a front side view thereof, with rear, right, and left side views being identical thereto.

The broken lines illustrate a ceiling fan, and portions of the ceiling fan motor housing. Shaded portions adjacent to the broken lines illustrate claimed portions that extend to the broken line. None of the broken lines form part of the claimed design.
